CLAIM

The ornamental design for a surface design for a garment as shown and described.

DESCRIPTION

FIG. 1 is a front elevational view of a surface design for a garment with an ornamental design applied to an exterior surface thereof;

FIG. 2 is an enlarged, front elevational view of a portion of the exterior surface of a section 2 of the surface design for a garment of FIG. 1;

FIG. 3 is a front elevational view of another embodiment of a surface design for a garment in a first, closed configuration;

FIG. 4 is a front elevational view of the surface design for a garment of FIG. 3 in a second, open configuration, an ornamental design applied to an interior surface thereof;

FIG. 5 is an enlarged, front elevational view of a portion of the interior surface of a section 5 of the surface design for a garment of FIG. 4;

FIG. 6 is a front elevational view of an additional embodiment of a surface design for a garment with an ornamental design applied to an exterior surface thereof;

FIG. 7 is an enlarged, front elevational view of a portion of the exterior surface of a section 7 of the surface design for a garment of FIG. 6;

FIG. 8 is a front elevational view of a further embodiment of a surface design for a garment in a first, closed configuration;

FIG. 9 is a front elevational view of the surface design for a garment of FIG. 8 in a second, open configuration, an ornamental design applied to an interior surface thereof; and, FIG. 10 is an enlarged, front elevational view of a portion of the interior surface of a section 10 of the surface design for a garment of FIG. 9.

The dash-dash-dash lines illustrate the environment of the claimed design and form no part of the claimed design. The short-dash, long-dash broken lines illustrate the division between the claimed design and unclaimed elements of the environment. The various surface treatments applied to the surfaces of the garments represent a contrast in appearance and do not illustrate any material, surface ornamentation, or surface decoration.
